John M. Maxwell
By Francis W. Clark,
attor.

UNITED STATES PATENT OFFICE.

JOHN M. MAXWELL, OF CHICAGO, ILLINOIS.

SKIAGRAPH.

SPECIFICATION forming part of Letters Patent No. 356,144, dated January 18, 1887.

Application filed May 17, 1886. Serial No. 202,488. (No model.)

To all whom it may concern:

Be it known that I, JOHN M. MAXWELL, a citizen of the United States, residing at Chicago, in the county of Cook and State of Illinois, have invented certain new and useful Improvements in Skiagraphs, of which the following is a specification.

My invention relates to devices for copying or duplicating pictures or natural objects; and 10 its object is to provide a device whereby such pictures or objects may be projected upon a drawing-surface over which the hand of the operator can freely pass, while at the same time he sees the picture T as it appears projected and the instrument which is copying it.

This device I have called a "skiagraph," or "shadow-writer," and it is illustrated in the accompanying drawings, wherein Figure 1 is a perspective of my device without a reflector. 20 Fig. 2 is the same with a reflector. Fig. 3 is a detail of the drawing-board. Fig. 4 is a detail of the transparent medium. Fig. 5 is a detail of the reflector. Fig. 6 is a detail of the reflector-supports. Fig. 7 is a detail of the object-support used with the reflector. Fig. 8 is a detail of the transparent-medium supports.

Like parts are designated by the same letter in all the figures.

A is a common drawing-board; B B, vertical 30 grooved posts thereon, held in place by the holes I I. C is an object-support, held erect on the board by means of a peg thereon and the hole J. D is a transparent medium, the surface of which reflects while at the same time light 35 passes through it. It is supported by the posts B B. E is a reflector, supported at an angle on the board by the wedges H H, held in place by the pegs thereon and the holes K. F is the drawing to be reproduced. G is the 40 projection thereof. It will be understood that, these parts can be greatly varied as to size, material, and angles at which they set.

The use and operation of my invention are as follows: The drawing is fastened to the 45 board at one side of the vertical transparent medium, and in this position a reflection can be had from the surface of the medium. In this reflection the picture will appear as if reversed and projected onto the drawing surface on the opposite side of the medium. At the same time the drawing paper or instrument or hand of the operator can be seen through the medium. If now the hand or instrument is carried over the board along the

apparent projected lines of the picture, a reversed copy thereof will be drawn on the opposite side of the medium. The eye, in looking at the surface of the medium, will see the reflected picture and also the lines made on the board or the hand and instrument which makes them. In the figure the hand and pencil are shown as seen in part through the medium as the picture is about to be completed. This picture is, as shown, reversed. If it is desired to make a direct picture, the mirror is 65 used, as in Fig. 2. Here the object or picture is placed erect on the board, as at C. From this point it passes through the medium and forms an image on the reflector. This image now occupies the position of the picture in the 70 original, Fig. 1, and this image is reflected from the surface of the medium as the drawing itself was in Fig. 1. This projected drawing is direct, however, as it is reversed twice—once on the mirror and once on the surface of 75 the medium.

The parts and their operation can be greatly varied by varying the angles at which they set. There must, however, be a transparent medium from which the reflected picture appears as if projected and through which the tracing-instrument can be seen in operation. 80

I claim and desire to secure by Letters Patent—

1. The combination of a drawing-board 85 having perforations on opposite sides with two posts, each adapted to be inserted into one of said apertures and each provided with a longitudinal groove, and a plate of glass of such size as to be received into the grooves of the 90 posts set up on the board.

2. The combination of the board A with the transparent mediums D and C and the reflector E.

3. In a skiagraph, the combination of a picture-holder, a drawing-board, a transparent medium, and a reflector. 95

4. In a skiagraph, the combination of a picture-support, a drawing-board adapted to hold the paper to receive the copy, a medium of 100 transparent material set upon and at an angle to the board, and a reflector set on the board and at an angle to the medium.

JOHN M. MAXWELL.
